FIG. 3

FIG. 4

FIG. 1 is a perspective view of a battery charger embodying my novel design.

FIG. 2 is a plan view of the same with the cover removed.

FIG. 3 is a cross-sectional view, partly in side elevation, taken along the line 3—3 in FIG. 2 with the cover in position.

FIG. 4 is a side elevational view of the same, the other side being substantially identical.

The dominant features of my new design are shown in solid lines in the drawing figures.

I claim:

The ornamental design for a battery charger, as shown and described.
